PROCESS FOR SMOKING FOODSTUFFS

Christian Thon, Oslo, Norway

Application October 4, 1938, Serial No. 233,302
In Germany October 6, 1937

3 Claims. (Cl. 99—229)

The present invention relates to a process for the smoking of food products by replacing the air contained in the cells or pores of the goods by smoke, by evacuation of the smoking chamber in which the goods to be treated are placed and introducing the smoke into the chamber. In accordance with the invention, the smoke gases are introduced into the smoking chamber at a pressure which is approximately the same as the pressure residing in the smoking chamber at any moment. It has previously been suggested to evacuate the smoking chamber before the smoking is started, but according to these previous suggestions the smoke is introduced into the evacuated smoking chamber at a pressure of one or more atmospheres, whereby a sudden expansion of the smoke gases takes place, accompanied by a condensation in part of the said gases. The condensation products will be deposited on the goods and give the same an undesirable appearance and taste. By the present invention this expansion and condensation are avoided and an even and thorough penetration of the smoke in the goods obtained, the goods being, as a rule, ready smoked when the pressure in the smoking chamber has reached the atmospheric pressure. Thus the smoking process according to the invention results in a quicker smoking through of the products wherefore a comparatively great smoking capacity will be obtained even with a comparatively small apparatus.

The smoke conveniently is produced during the smoking process at approximately the same pressure as the gradually increasing pressure in the smoking chamber. In order to achieve this, the chamber wherein the smoke is developed may be evacuated before the smoking is started. This evacuation may be carried out jointly with the evacuation of the smoking chamber, or, when the smoke producing chamber has a small volume as compared with the smoking chamber, by bringing the smoke producing chamber into communication with the already evacuated smoking chamber.

An apparatus for carrying out the process according to the invention conveniently may be so constructed that the smoke producing chamber is arranged within, or in open connection with, the smoking chamber, in such a manner that the smoke producing chamber is evacuated simultaneously with the smoking chamber, but it is also possible to connect the smoke producing chamber to the smoking chamber by means of a conduit provided with a stop valve or the like. In this case the smoke producing chamber may

be evacuated separately or by being put in connection with the already evacuated smoking chamber. The smoke production is regulated during the smoking by means of an adjustable air inlet valve in connection with the smoke producing chamber, in such a manner that at any time only the quantity of air required for the production of smoke of the desired pressure is introduced. Thus, only the quantity of smoke required for the carrying out of the process is produced, whereby it is economically possible to use the best and purest qualities of fuel, for instance aromatic woods, thereby giving the goods any desired aroma and flavour.

15 The smoke temperature conveniently is adjusted by means of a cooling jacket enclosing the connection conduit between the smoke producing chamber and the smoking chamber and, if desired also the smoke producing chamber and/or the smoking chamber.

20 The accompanying drawing illustrates schematically an example of an apparatus for carrying out the process according to the invention. Figure 1 is a vertical longitudinal section through an apparatus wherein the smoking chamber is in communication with the smoke producing chamber, and Figure 2 a vertical cross section of the smoking chamber.

25 In the figures, 1 is the smoking chamber consisting of a cylindrical container which is closed at one end and at the other end provided with a door 2, with a quick closing arrangement. The interior of the smoking chamber is provided with laths, shelves, nets or the like for the placing of 30 the goods to be treated, 3 is a water jacket enclosing the cylindrical wall of the smoking chamber and 4 an insulation, covering the end walls of the chamber. At 5 the chamber is connected to a ventilator for the withdrawal of unused 35 smoke from the chamber after completed treatment, and at 6 the chamber is connected to a vacuum pump 7 for the evacuation of the chamber before the smoking process is started. Further, the chamber may be provided with an air inlet valve 8, a thermometer 9, a manometer 10 and observation windows 11.

40 By means of the conduit 12 which may be provided with a stop valve 24, the chamber is connected to the smoke producing chamber 13, which 45 has the form of a frustum of a cone with the smaller base facing downwards. At the top this chamber is closed by means of a cover 15 provided with a thermometer 14 and at the bottom the chamber is provided with a turnable grid 16 and ash pan 17. This container also is enclosed

by a water cooling jacket 18 and is provided with observation windows 19. In the lower portion of the container is an electric filament 20 for the ignition of the fuel, and the air supply for the smoke production is controlled by means of the air inlet valve 21. In order to prevent the flames from entering the chamber 1 or the conduit 12 the combustion portion of the chamber 13 suitably is covered by a fine mesh grid 22. The chamber also may be provided with a safety valve 23.

The treatment suitably is carried out by introducing fuel in predetermined quantities into the smoke producing chamber and inserting the grid 22. The cover 15 thereafter is applied and the goods to be treated are placed in the chamber 1, whereafter the door 2 is closed and the vacuum pump 7 started. When the desired vacuum is obtained a current is passed through the filament until ignition temperature of the fuel is reached, whereupon the valve 21 is slightly opened. By means of the valve 21 the smoke production is so controlled that the pressure in the chamber 1 is gradually increased until atmospheric pressure is reached, at which time the smoking as a rule is completed, all pores and cells of the goods then being completely filled with smoke of atmospheric pressure.

What I claim is:

1. A method for smoking food products comprising the steps of evacuating an enclosure containing both the products to be smoked and the smoke producing fuel, igniting the fuel, gradually admitting a combustion supporting gas to the enclosure until atmospheric pressure is reached, whereby the smoke is produced at approximately the pressure existing in the pores and cells of the vacuum treated products and

5 penetrates said pores and cells as the ambient pressure within the enclosure is increased, and whereby deleterious condensation of products of combustion in and upon said food products is eliminated.

2. A method for smoking food products comprising the steps of evacuating an enclosure containing both the products to be smoked and the smoke producing fuel, igniting the fuel, gradually admitting a combustion supporting gas to the enclosure in the vicinity of said igniting fuel, whereby the smoke is produced at approximately the pressure existing in the pores and cells of the vacuum treated products and penetrates said pores and cells as the ambient pressure within the enclosure is increased, and whereby deleterious condensation of products of combustion in and upon said food products is eliminated.

3. A method for smoking food products comprising the steps of evacuating a smoke generating chamber and a chamber containing the products to be smoked both to substantially the same degree, producing smoke gases in said generating chamber at approximately said degree of 15 sub-atmospheric pressure, providing free inter- 20 communication between said chambers, and gradually supplying combustion air to said generating chamber at a rate sufficient to maintain combustion of the smoke producing fuel, where- 25 by the smoke is produced at approximately the pressure existing in the pores and cells of the vacuum treated products and penetrates said pores and cells as the ambient pressure within the enclosure is increased, and whereby deleterious condensation of products of combustion in and upon said food products is eliminated.
